UNITED STATES PATENT OFFICE.

FRANK BARNES, OF HARPERS FERRY, IOWA.

RAILROAD-CROSSING SIGNAL.

Application filed May 16, 1924. Serial No. 713,792.

To all whom it may concern:

Be it known that I, FRANK BARNES, a citizen of the United States, residing at Harpers Ferry, in the county of Allamakee and State of Iowa, have invented new and useful Improvements in Railroad-Crossing Signals, of which the following is a specification.

This invention relates to a signal apparatus, particularly to that type designed for use on railroads, and has for its object the provision of a novel signal mechanism which will operate automatically, upon the approach of a train, for giving a visible signal at a road crossing whereby to warn motorists, pedestrians, and all interested parties of the approach of a train, the device being a great safeguard against injury and loss of life.

An important object is the provision of a device of this character which is mechanically operated upon the approach of a train, the passage of the train along the track being the sole means for effecting movement of the various parts embodied in the invention.

Another object of the invention is to provide a signal mechanism which will automatically return to its normal or inoperative position after the train has passed by the crossing.

Still another object is the provision of a mechanism of this character embodying various detailed features of construction and arrangement which will insure operation at all times and which will make it unnecessary for the signal to depend to any extent whatsoever upon manual manipulation.

An additional object is the provision of a signal apparatus of this type which will be simple and inexpensive in manufacture and installation, positive in action, efficient and durable in service, and a general improvement in the art.

With the above and other objects and advantages in view, the invention consists in the details of construction to be hereinafter more fully described, claimed, and illustrated in the accompanying drawings, in which:

Figure 1 is a fragmentary plan view of a railroad track and road crossing, showing the application of the invention.

Figure 2 is a sectional view taken longitudinally of the track and showing a side

elevation of the various operating parts of the mechanism.

Figure 3 is a section on the line 3—3 of Figure 2.

Figure 4 is a vertical section taken longitudinally of the track and showing, on a larger scale, one of the signal members in normal or inoperative position.

Figure 5 is a section taken across the trackway and illustrating an elevation of the signal actuating mechanism.

Figure 6 is an enlarged detail sectional view showing the double dog holding means for the operating rack.

Figure 7 is a detail section on the line 7—7 of Figure 5.

Referring more particularly to the drawings, the letter A designates the railroad track intersected by a road crossing B which it is desired to protect by means of the signal device forming the basis of the present application.

In carrying out the invention, I provide along the trackway, at opposite sides of the crossing B, suitable supporting and bearing brackets 10 which may conveniently be mounted on the undersides of ties and within which are journaled drums 11 about each of which is trained flexible members 12 and 13 secured at one end to the drum. The free end of the flexible member 12 has connected therewith a spring 14 which has its other end connected with a depending bracket 15 mounted on the tie D adjacent the tie C on which the bracket 10 is mounted. One end 90 of the cable 13 is connected with a vertically extending plunger rod 16 slidable through a suitable guide 17 on the tie C and having an enlarged head adapted to be engaged by some suitable element depending from the locomotive or other portion of the train travelling upon the track. Obviously, the train approaching the crossing from either side will cause depression of the plunger rod 16 and partial rotation of the drum 11. 100

To take the advantage of the above mentioned conditions, I provide signal devices mounted to extend across or partly across the crossing B in elevated position, which signal devices include upright supporting posts 18 upon which are pivoted, as at 19, elongated arms 20 equipped at one end with a weight 21 which will operate normally to hold the arms in elevated or inoperative position. If desired, the free end of each arm 110

- 2
- may be equipped with a suitable signal lantern 22 of the oil or electric type, as preferred. Details of this feature are not given as they really form no part of the present invention. If desired, each arm 20 may have depending therefrom a stop arm 23 adapted to engage the roadway for limiting downward swinging movement of the signal. While the counterbalancing weight 10 might be used as above described, it is really preferable that they be mounted on the shorter arms of the signal members to partially compensate for the added weight of the long arms so as to make the swinging movement, by the means to be described, more easily accomplished.
- Located beneath the roadbed at a point near or at the crossing B is a suitably enclosed or built in recess 24 within which are mounted uprights 25 carrying bearings 26 for a shaft 27 which carries a pair of winding drums 28 and 29. Inwardly of the uprights 25 is another pair of uprights 30 between which is slidably mounted a rack bar 31 which meshes constantly with a gear 32 on the shaft 27. Connected with the upper end of the rack bar is a cable or other flexible member 33 which is trained over a guide pulley 34 and which carries a weight 35 which operates to hold the rack bar normally in its uppermost position.
- Pivottally connected at 36 with the lower end of the rack 31 are links 37 which diverge downwardly and which are pivotally connected as at 38 with the inner ends of a pair of bars 39 slidable through bearings 40 mounted on the lower element 41 of a frame construction including uprights 42. The uprights 42 are mounted at opposite sides of the trackway adjacent the highway crossing B and constitutes supports for the signal, the above described members 18 being either secured to or formed as continuations of the uprights 42. Connected with the outer ends of the bars 39 are cables or other flexible members 43 trained over guide pulleys 44 and 45 and connected with the signal arms 20 as shown at 46. Obviously, when the rack is moved either up or down, as the case may be, the flexible members 43 will operate to swing the signal arms.
- The flexible members 18 above described as having one end connected with the plunger 16 have their other ends brought 55 to and into the compartment or recess 24 and secured to and wrapped about the drums 28 and 29 respectively so as to effect turning movement thereof when the plungers 16 are depressed upon passage of a train.
- It will be noted that the counterbalancing weight 35 always tends to move the rack 31 upwardly for holding the signal arms normally in inoperative position. On account of this fact it becomes necessary to provide 60 a catch device or some means for prevent-
- ing the signal arms from moving to inoperative position when such is not desired. In carrying out this feature, I provide a supporting bracket 47 on one of the uprights 70 30, and upon this bracket there is pivoted, at 48, a double ended pawl 49 which cooperates with the rack 31 and which may have either end engaged therewith. Connected with the ends of this double ended pawl are coil springs 50 which are arranged 75 in crossed relation and which are connected at diametrically opposite points on the shaft 27. The drums 28 and 29 are fast upon the shaft 27 but it will be observed that the mounting for the gear 32 is such 80 as to permit a certain amount of lost motion owing to the fact that the gear is formed with arcuate slots 51 through which pass pins 52 carried by one end of the drum 28.
- In the operation of the device, let it be assumed that the signal arms are in inoperative position as shown in Figure 4. When a train approaches the crossing from either side thereof, the foot or shoe element, not 90 shown, carried by the train will engage one or the other of the heads 17 as the case may be and depress the plunger 16. When this is done the drum 11 will be rotated, against the resistance of the spring 14, and a pull 95 will be exerted upon the cable 13. The tension on the cable tends to rotate the drum 28, or 29 as the case may be, and the first result is that one or the other of the springs 50 will pull upon the double ended pawl 100 49 and disengage it from the rack 31. As the turning movement continues, the pins 52 will engage the ends of the slots 51 and turn the gear 32. The rotation of the gear 32 is imparted to the rack bar whereupon 105 upward movement of the links 37 results and these links exert a pull upon the bars 39 and flexible members 43 so that the signal arms 20 will be swung downwardly into horizontal or signalling position, clearly 110 indicating to motorists, tourists, pedestrians and all interested parties that a train is approaching. After the train has gone by it is quite apparent that the springs 14 will operate to return the plunger devices 115 15 to normal position so that all of the parts will be restored to normal.
- From the foregoing description and a study of the drawings, it will be apparent that I have thus provided a simply constructed and easily installed automatic signal device which will be positive in its action and which will require no power other than that derived from the passage of a 120 train. The device will be found to be a great life saver inasmuch as it will prevent persons from crossing the trackway in ignorance of the fact that a train is approaching.
- While I have shown and described the 130

preferred embodiment of the invention, it is to be understood that I reserve the right to make such changes in the form, construction and arrangement of parts as will not depart from the spirit of the invention or the scope of the subjoined claims.

Having thus described the invention, I claim:

1. In a railroad crossing signal device, vertically swingable signals mounted at opposite sides of a trackway adjacent a crossing, a horizontal shaft, drums secured upon said shaft, a gear mounted on said shaft and having a certain degree of lost motion, a vertically movable rack meshing with said gear and operatively connected with the signal arms, and trip operated drums mounted along the trackway at opposite sides of the crossing and carrying cables secured to and wrapped about the first named drums.

2. In a railroad signal device, vertically swingable signals mounted at opposite sides of a trackway adjacent a crossing, a horizontal shaft, drums secured upon said shaft, a gear mounted on said shaft and having a certain degree of lost motion, a vertically movable rack meshing with said gear and operatively connected with the signal arms, trip operated drums mounted along the trackway at opposite sides of the crossing and carrying cables secured to and wrapped about the first named drums, said second named drums being double and carrying other cables secured to and wrapped thereto and having spring tension applied thereto.

3. In a railroad signal device, vertically swingable signals mounted at opposite sides of a trackway adjacent a crossing, a horizontal shaft, drums secured upon said shaft, a gear mounted on said shaft and having a certain degree of lost motion, a vertically movable rack meshing with said gear and operatively connected with the signal arms,

trip operated drums mounted along the trackway at opposite sides of the crossing and carrying cables secured to and wrapped about the first named drums, spring means for opposing rotary movement of said second named drums.

50

4. In a railroad crossing signal device, vertically swingable signals mounted at opposite sides of a trackway adjacent a crossing, a horizontal shaft, drums secured upon said shaft, a gear mounted on said shaft and having a certain degree of lost motion, a vertically movable rack meshing with said gear and operatively connected with the signal arms, trip operated drums mounted along the trackway at opposite sides of the crossing and carrying cables secured to and wrapped about the first named drums, spring means normally holding said second named drums in normal position, and a catch device operatively connected with said shaft and engaging said rack bar.

65

5. In a railroad crossing signal device, vertically swingable signals mounted at opposite sides of a trackway adjacent a crossing, a horizontal shaft, drums secured upon said shaft, a gear mounted on said shaft and having a certain degree of lost motion, a vertically movable rack meshing with said gear and operatively connected with the signal arms and trip operated drums mounted along the trackway at opposite sides of the crossing and carrying cables secured to and wrapped about the first named drums, spring means opposing rotation of the second named drums, a double ended catch device operatively engaging said rack bar, and a pair of springs connected with said shaft, arranged in crossed relation and connected with the ends of said double ended catch device.
